UNITED STATES PATENT OFFICE.

EDWIN H. PORTER AND BURLEIGH CURRIER, OF PHILADELPHIA,
PENNSYLVANIA.

MAGNETIC TACHOMETER.

No. 806,363.

Specification of Letters Patent.

Patented Dec. 5, 1905.

Application filed June 17, 1905. Serial No. 265,887.

To all whom it may concern:

Be it known that we, EDWIN H. PORTER and BURLEIGH CURRIER, citizens of the United States, residing at Philadelphia, in the county of Philadelphia and State of Pennsylvania, have invented certain new and useful Improvements in Magnetic Tachometers, of which the following is a specification.

Our invention relates to improvements in magnetic tachometers.

The object of our invention is to produce a magnetic tachometer that is simple, accurate, and permanently reliable when indicating the speed of revolving shafts to which it may be applied.

A further object of our invention is to produce a magnetic tachometer of a size readily carried in the pocket, free from parts easily deranged, and having a permanent magnetic circuit so constructed as to maintain a maximum magnetic flux through an armature for a given space and give a maximum torque to the armature when rotated at a given speed; also, to provide a practically closed magnetic circuit, so as not to be affected by external magnetic fields.

A still further object is to provide a magnetic circuit which will be permanent through long periods of time, insuring permanent accuracy.

A still further object is to provide the tachometer with a simple arrangement of variable-speed gears to give a variable-speed ratio between the revolving magnets and their driving-shaft, thus making the instrument readily adaptable to use on widely-varying speeds.

Magnetic tachometers as heretofore constructed are necessarily large and bulky and their construction has been such that the magnetic strength, and therefore the accuracy, rapidly deteriorates, and for the above reasons they have not been a commercial success.

Our invention consists in a magnetic tachometer having two permanent multipolar concentric magnets having poles of opposite polarity facing each other and embracing in the air-gap between the poles a conducting cylindrical armature suitably pivoted and equipped with an indicating pointer and scale.

The magnet system is provided with a simple system of change-gears and a pointed

spindle to engage with the rotating shaft whose speed is to be measured.

Referring to the drawings, Figure 1 is a plan view of our improved tachometer. Fig. 2 is a sectional view on line 2 2, Fig. 1. Fig. 3 is a plan view of the magnet detached. Fig. 4 is a plan view of the armature detached, and Fig. 5 is a detached view of the gear-casing.

In the drawings, A is a casing consisting of a base A' and the side walls A², in which are secured the dial-plate A³ and the glass A⁴ for protecting the same. The base A' has a shaft B mounted therein, having squared ends b and b', adapted to receive the shank C of the spindle C', which is provided with a pointed end c, adapted to be held in the center mark upon the end of a revolving shaft the speed of which is to be indicated. A variable-speed mechanism D is adapted to be interposed between the spindle C' and the shaft B, which will be more fully described hereinafter. A bevel gear-wheel B' is mounted upon the shaft B, which drives the bevel gear-wheel E, attached to the sleeve E', carrying the rotatable magnetic structure F. Said sleeve is mounted upon a hollow shaft A⁵, projecting from the base A'. Mounted within the hollow shaft A⁵ is a pivotal shaft G, which rests upon a jeweled bearing g, and its upper portion is guided in a jeweled bearing g', carried by the dial-plate A³. Upon the upper end of the said pivotal shaft is an indicating-pointer G', which is held in its normal position, as shown in Fig. 1, by a coil-spring G², having one end attached to the pivotal shaft G and its opposite end attached to a post G³ on the dial-plate A³, against the action of which spring the indicator-hand G' is rotated over the dial-plate A³, which is provided with suitable graduations.

The rotatable magnetic structure F is constructed in two parts, H and H', each of which is provided with radial polar projections h and h', so arranged as to form an air-gap between their adjacent ends and between which is suspended the cylindrical armature I, which is carried upon the pivotal shaft G by arms i. The two portions H and H' of the rotatable magnetic structure are concentrically mounted upon a disk E², carried by the sleeve E'. The disk E² forms a base for the magnets H.

- and H', so that the said magnets H and H' rotate together. The magnets H and H' are made up of hardened steel laminations h, as shown in Fig. 2, which are rigidly secured together by pins h'. The laminations of the magnet H' form a central hub having an aperture to receive the sleeve E', and from which hub the radial polar projections h extend, while the laminations of the magnet H form an annular yoke from which the radial polar projections h extend, thus completing a permanent magnetic circuit between the said radial polar projections h and h', as clearly shown in Fig. 3. The magnets H and H' are permanent magnets, and the projections h and h' form poles N and S. The cylindrical armature I is non-magnetic and is mounted between the poles N and S of the magnets H and H', as above described.
- 20 Our invention depends for its action on the well-known principle of the interaction of electric currents induced in an armature by a rotating field with the field that induces them.

By applying the point c of the spindle C' to a revolving shaft the motion will be communicated to the shaft B and through the bevel gear-wheels B' and E to the magnetic structure F, thus causing the magnets H and H' to revolve, the effect of which is to give a torque 25 to the armature I and cause the indicator-hand to move over the dial in the direction of the arrow, Fig. 1, the magnets maintaining a permanent maximum magnetic flux through the armature. The arc of travel of the indicator-hand is proportional to the speed at which said magnets are rotated, and as the speed of said magnets corresponds to the speed of the shaft to be indicated the readings may be readily taken from the dial, which is properly 30 calibrated.

It is desirable for wide ranges of speed to increase or reduce the speed of the tachometer in relation to the speed of the shaft to be indicated. We therefore provide a variable-gear mechanism D, which may be interposed between the spindle C' and the shaft B. This mechanism consists of a casing D', in which are mounted shafts D² and D³, carrying differential gear-wheels D⁴ and D⁵, meshing with each other. The shafts D² and D³ are each provided with squared ends at one side of the casing to receive the shank of the spindle C', and at their inner ends they are provided with square apertures to fit over the ends of the shaft B. The variable-gear mechanism is detachable—that is to say, that the casing D' may be attached to the casing A' by means of the dowel-pins d, so that either the shaft D², carrying the larger gear-wheel, may be connected to the shaft B, or the shaft D³, carrying the smaller gear-wheel, may be attached to the shaft B. The spindle C may be placed on either shaft D² or D³. When in the position shown in full lines, Fig. 2, the speed ra-

tio is not changed. When in the position 65 shown in dotted lines, the speed ratio will be reduced, as the smaller gear-wheel D⁵ will be the driver. If the casing D' is reversed with the larger gear-wheel, D² will be the driver, and the speed ratio will be increased and additional series of calibrations or a constant is provided on the scale for correctly indicating the speed with the different ratio of gears. The casing D' may be transferred to the opposite side of casing, so as to connect the shaft 70 D² or D³ to the opposite end of shaft B, reversing the relative direction of rotation of spindle C and magnets H and H'.

Having thus described our invention, we claim and desire to secure by Letters Patent— 80

1. In a magnetic tachometer, the combination of a permanent magnetic structure consisting of two concentric coaxial members embracing a plurality of permanent magnetic poles, the same connected together and revolvably mounted, a cylindrical metallic conducting-armature movably mounted between the poles of said magnetic structure, an indicating-pointer and a resisting-spring for said armature, a calibrated scale and means for rotating said magnetic structure, substantially as described. 85

2. In a magnetic tachometer, the combination of a permanent magnetic structure consisting of two concentric, coaxial, circular laminated field members of a multipolar type, poles of opposite polarity of each field member facing each other, the whole revolvably mounted and embracing between opposite poles a cylindrical, metallic, conducting-armature, a resisting-spring for said armature, an indicating-pointer on said armature, a calibrated scale and means for rotating said magnetic structure, substantially as described. 90

3. In a magnetic tachometer, the combination of two coaxial, concentric laminated, multipolar, permanent magnets, rotatably mounted together on a bearing, said magnets having poles of opposite polarity adjacent each other, a conducting cylindrical armature 105 embraced by said magnets, a suitable pivotal shaft carrying said armature, an indicating-pointer a resisting-spring and a calibrated scale, the whole operatively connected together, substantially as described. 110

4. In a magnetic tachometer, the combination of two permanent magnets of a circular multipolar type, one having outwardly-projecting poles, the other inwardly-projecting poles, the two magnets concentrically mounted together with opposite poles adjacent, the same arranged to revolve coaxially, a driving-shaft and a detachable gear mechanism for driving said magnets, a conducting cylindrical armature mounted between the poles of said magnets on pivots to allow of oscillation, a resisting-spring connected to said armature, an indicating-pointer carried by said arma- 115 120 125

ture, and a calibrated scale, substantially as described.

5. In a magnetic tachometer, the combination of a casing, a bearing having a driving-shaft mounted therein, a hollow vertical shaft, a magnetic structure mounted upon the same, a bevel gear-wheel on said driving-shaft and on said magnetic structure meshing together, a pivotal shaft mounted within said hollow shaft, an armature carried by said pivotal shaft and embraced by said magnetic structure, a resisting-spring and an indicating-

pointer on said pivotal shaft, a calibrated scale and means for connecting said driving-shaft with a revolving shaft, substantially as described. 15

In testimony whereof we affix our signatures in presence of two witnesses.
